DESIGN.

W. WILKINSON.

SPRINKLING CAN.

No. 16,822.

Patented July 27,

UNITED STATES PATENT OFFICE.

WILLIAM WILKINSON, OF PHILADELPHIA, PENNSYLVANIA.

DESIGN FOR A SPRINKLING-CAN.

SPECIFICATION forming part of Design No. 16,822, dated July 27, 1886.

Application filed September 10, 1885. Serial No. 176,748. Term of patent 7 years.

To all whom it may concern:

Be it known that I, WILLIAM WILKINSON, a citizen of the United States, residing in the city and county of Philadelphia, State of Pennsylvania, have invented and produced a new and original Design for a Sprinkling-Can, of which the following is a specification, reference being had to the accompanying photographic illustration, forming part thereof.

10 The leading feature of my design for a can is the body of cylindrical form, having a surface ornamentation of connected pyramids, the lower edge of each side thereof being of equal length and of a curve form, coinciding 15 with the surface of the cylinder, and a horizontal raised band or stripe on the upper plain portion or rim thereof.

10 A represents the body of a sprinkling-can, the surface whereof is of the form of connected 20 pyramids B, the lower edge of each side thereof being of equal length and of a curve form,

coinciding with the surface of the cylinder at the line of connection of the same.

C represents a plain rim at the top of the body, the same adding variety to the form of 25 the body.

D represents a raised horizontal stripe or band on the said rim C.

I claim—

A design for a can having a body of cylindrical form, with a surface ornamentation of connected pyramids, the base of each side thereof of equal length and of the form of a curve corresponding to the line of connection with the cylinder, and an upper portion or 35 rim, C, with a raised horizontal stripe or band, D, substantially as shown.

WILLIAM WILKINSON.
